US0D1064878S

(12) **United States Design Patent** (10) Patent No.: **US D1,064,878 S**
(45) Date of Patent: ** Mar. 4, 2025

(54) **CONTROLLER**

- (71) Applicant: **Dometic Sweden AB**, Solna (SE)
- (72) Inventors: **Eric Schuh**, Stevensville, MI (US);
Clayton Hendry Meyers, Paw Paw, MI (US); **Samuele Meda**, Chichester (GB);
Jens Nybacka, Nacka (SE)
- (73) Assignee: **Dometic Sweden AB**, Solna (SE)
- (**) Term: **15 Years**
- (21) Appl. No.: **29/919,786**
- (22) Filed: **Dec. 6, 2023**

(74) Attorney, Agent, or Firm — Dinsmore & Shohl LLP

(57) **CLAIM**

The ornamental design for a controller as shown and described.

DESCRIPTION

FIG. 1 is a perspective view of a design of a controller; FIG. 2 is a front view of the controller of FIG. 1; FIG. 3 is a rear view of the controller of FIG. 1; FIG. 4 is a first side view of the controller of FIG. 1; FIG. 5 is a second side view of the controller of FIG. 1; FIG. 6 is a top view of the controller of FIG. 1; and, FIG. 7 is a bottom view of the controller of FIG. 1.

1 Claim, 5 Drawing Sheets
